UNITED STATES PATENT OFFICE.

SIDNEY S. RAND, OF NEW YORK, N. Y.

PERMANENT HAIR WAVER.

Application filed August 10, 1920. Serial No. 402,544.

To all whom it may concern:

Be it known that I, SIDNEY S. RAND, a citizen of the United States, residing at New York, in the county of New York and State of New York, have invented certain new and useful Improvements in Permanent Hair Wavers; and I do hereby declare the following to be a full, clear, and exact description of the invention, such as will enable others skilled in the art to which it appertains to make and use the same.

This invention relates to permanent hair wavers, and particularly to permanent hair wavers which are operated by electricity. The objects of the invention are to provide improved means for supporting heating elements; to avoid cutting the flexible support for said heating elements; to provide improved means for plugging in or connecting the heating elements with the source of electrical supply; to render the device economical of construction, strong and attractive; to obtain a construction which complies with the underwriter's requirements; to secure simplicity of construction and operation, and to obtain other advantages and results as may be brought out in the following description.

Referring to the accompanying drawings, in which like numerals of reference indicate similar parts throughout the several views,

Figure 1 is a side elevation of a permanent hair waving device constructed in accordance with my invention;

Figure 2 is a vertical central section of a portion of the upper part thereof;

Figure 3 is a plan view of a portion of Fig. 2;

Figure 4 is a central vertical section of the receptacle member, showing one of the receptacles in section;

Figure 5 is a plan view of said receptacle member;

Figure 6 is a perspective view of a portion of the receptacle supporting device removed from said member;

Figure 7 is a plan view of a portion of a modified construction of receptacle member;

Figure 8 is a sectional view on line 8—8 of Fig. 7;

Figure 9 is a perspective view of one of the plugs adapted to cooperate with a receptacle of said modified receptacle member;

Figure 10 is a diagrammatic view showing the wiring plan for said modified receptacle member;

Figure 11 is a plan view of a further modified construction of receptacle member;

Figure 12 is a longitudinal sectional view of Fig. 11 taken in the plane of the bus-bar; and

Figure 13 is a perspective view of the attachment member for use in connection with the modified attachment member of Figs. 11 and 12.

In the specific embodiment of the invention illustrated in said drawings, and referring more particularly to Figures 1-6, the reference numeral 1 indicates the plurality of heating elements supported by means of their flexible electrical wires 2. The other ends of the wire 2 carry attachment plugs 3 adapted to be inserted in receptacles 4 carried by a receptacle supporting member 5. The receptacle supporting member is in turn carried by a chandelier stem 6 supported from the outlet box 7 in the ceiling from which the wires 8 are connected for supplying the electric current to the heaters. The wires 8 connect through the stem 6 to the receptacle member 5 and are properly connected with other wires 9 within said receptacle member, said wires 9 being attached to the receptacle and thereby conducting the current so it may pass to the flexible wires 2 and to the heating elements 1. As may be seen, the receptacles and plugs are on the upper side of the receptacle member 5 and the wires from the plugs extend upwardly therefrom and are connected by means of flexible supports, such as cords 10 which pass over pulleys 11 and have weights 12 attached to their opposite ends by means of which the heating elements are counter balanced and will stay at whatever elevation they are put. The pulleys 11, for convenience, are attached to a canopy 13 carried in a convenient manner from the chandelier stem. This canopy also supports a ring 14, as by arms 15, said ring having spaced perforations about its circumference through which the flexible supports or cords 10 are adapted to pass thereby separating the weights 12 and preventing the cords from becoming entangled or interfering with the flexible wires 2. Preferably the perforations through the

canopy are of a size to permit the passage of the cords 10 therethrough.

ring 14 have gromets 16 therein so as to provide a smooth surface over which the flexible supports 10 will pass and thus avoid cutting them or unnecessarily causing them 5 to wear out.

While I have more particularly described the invention as employing tubes 32, it is to be understood that other stiffening members may be employed, and by way of example I 10 have shown a rod 33 in Figure 16. In that case, the wire which in the previous case passed through the tube, will in this case be positioned adjacent the rod and will pass through a hole 35 for that purpose in the 15 head.

The receptacle member 5 as shown in Figures 4 and 5 more particularly, comprises a housing 37 preferably shaped as a cross with four substantially equal arms. The 20 chandelier stem 6 attaches to the housing where the arms cross, and each arm carries a plurality of receptacles 4. In the present disclosure, said housing 37 is hollow and the upper wall thereof has appropriate holes 25 therein for receiving the receptacles. At the top of said housing and surrounding each receptacle is a collar 38 having depending ears 39 at its inner periphery. To said depending ears are connected the arms 40 of 30 a yoke 41 which underlies the receptacle and provides means for rigidly securing the receptacle in place, it being understood that the collar is secured to the housing as by soldering or otherwise. As may be seen in 35 Figure 4, the receptacle has a central screw which screws into the upper end of a stud 43 depending through a hole 44 in said yoke, and a screw 45 from the outside of the housing inserted upwardly enters the lower end 40 of the stud thereby retaining it and the receptacle in place in the housing.

In the disclosure being described, the receptacles preferably employed are of the type which each receive the two wires representing opposite polarity and with which are used attachment plugs having two prongs, one for each wire. All of the receptacles are connected in parallel and any one of the plugs may be inserted in any one 45 of the receptacles. Furthermore, as shown in Figure 1, each plug supplies two or, if necessary, more heating elements. This becomes necessary in order to shorten the arms of the housing as much as possible and at 50 the same time feed all of the heating elements. The naturally clumsy dimensions of the receptacles requires considerable space for each. It may be added, however, that the current supplied to two heating elements 55 is more than one receptacle may safely carry under some conditions, and it therefore becomes desirable to obtain means for attaching each heating element electrically independent of the other elements.

60 In carrying out this feature of my invention,

tion, and referring to Figures 7 to 10, it will be observed that a housing 46 of cross shape as before is provided. The upper side of this housing is provided with parallel series of holes in which are carried individual receptacles 47 of a type requiring comparatively little space. By way of illustration the receptacles may consist of an outer tube or body 48 of insulatory material within which is inserted a metal contact member 49 70 axially of said body and in turn tubular at its upper end for receiving a split resilient prong 50 on the attachment plug 51. The electric wire is attached to said contact member 49 by a screw 52 inserted through an 75 appropriate hole in the side of the body. The attachment plug is similarly constructed, providing a cylindrical insulatory body 5 within which the wire, as 53, is attached to the contact member by screw 54. 80 Each receptacle and each plug in this instance represent a single pole, and each preferably has only a single wire connected thereto.

It is to be observed that the receptacles 90 in this disclosure are arranged in two rows side by side, and in order to add to the simplicity of the device, I arrange that the receptacle next any other receptacle either crosswise or lengthwise of the rows, shall 95 be of opposite polarity to the first one. This is accomplished by wiring the receptacles as diagrammatically illustrated in Figure 10. As therein shown the wires 55 and 56 representing opposite polarity, are 100 diagonally crossed to the diagonally opposite receptacles so that every other one of the two rows are of the same polarity and the intermediate ones are of the other polarity.

The structure may be further simplified, 105 if so desired, as shown in Figures 12 to 13, wherein the reference numeral 57 designates an insulatory body having a plurality of recesses 58 arranged opposite each other in rows side by side. The bottom of the body 110 57 may be longitudinally grooved as at 59 for receiving bus bars 60, 60, one bus bar underlying each row of recesses 58. Carried by the bus bars are series of resilient contact members 61 properly spaced so as 115 to enter the recesses in assembling the several parts. A bottom closure 62 protects the bus bar from short circuiting through outside contact and obviously the bus bars may be attached to either the body or the 120 closure as found most desirable.

The attachment plug 63 preferred for use in connection with this last described receptacle, comprises an insulatory body 64 from which depend attaching prongs 65. In the 125 plane of said prongs, the body is preferably flattened so as to enable the plugs to be arranged side by side in the smallest space practicable. So as to prevent inserting the prongs in consecutive holes of the same row, 130

the prongs are preferably of the polarized type, that is, shaped in such manner that they cannot be inserted wrong. In the present instance this is shown accomplished by 5 constructing them of T-shape in cross section and making the holes in the body of the receptacle also T-shaped in cross section at the top as at 66.

Obviously other detail modifications and 10 changes may be made in the construction of my improved permanent hair waver, and I do not wish to be understood as restricting myself to the exact structures shown, except as set forth in the following claims when 15 construed in the light of the prior art.

I claim:—

1. The combination of a receptacle member, a canopy, heating elements, said heating elements having flexible electrical connections 20 extending therefrom to the receptacle member, and counter-balancing means carried from said canopy and adapted to counterbalance said heating elements so as to permit said elements to be raised or lowered and 25 remain at the position where put.

2. The combination of a receptacle member, a canopy, heating elements, said heating elements having flexible electrical connections extending therefrom to the receptacle 30 member, attachment plugs on said flexible connections for attachment to said receptacle member, and counter-balancing means carried from said canopy and adapted to counterbalance said heating elements so as 35 to permit said elements to be raised or lowered and remain at the position where put.

3. The combination of a receptacle member, a canopy, heating elements, attachment 40 plugs in said receptacle member, a plurality of flexible electrical connections from each of said attachment plugs connecting with separate heating elements, and means carried from said canopy and adapted to counterbalance said heating elements so as to permit 45 said elements to be raised or lowered and remain at the position where put.

4. The combination of a receptacle member, a canopy, heating elements, said heating elements having flexible electrical connections 50 comprising a pair of wires, separate attachment plugs for each of said wires for attachment to said receptacle member, and counter-balancing means carried from said canopy and adapted to counterbalance 55 said heating elements so as to permit said elements to be raised or lowered and remain at the position where put.

5. In a device of the character described, the combination of a receptacle member having 60 a plurality of openings for receiving attachment plugs, hair curling heating elements, polarized attachment plugs in said receptacle member thereby necessitating proper insertion of said plugs in said member, and flexible electrical connections from 65

said attachment plugs to said heating elements.

6. In a device of the character described, the combination of a housing having a plurality of upwardly facing receptacles, means 70 for supporting said housing, and heating elements adapted to be connected to said upwardly facing receptacles.

7. In a device of the character described, the combination of a canopy, a stem depending 75 from said canopy, a receptacle housing carried by said stem, and a plurality of hair curling heat elements adapted to be connected with the receptacles of said housing.

8. The combination of a housing having 80 cross arms with a plurality of receptacles therein, supporting means above said housing including a stem for supporting the housing, a plurality of heating elements and means carried by the canopy substantially 85 above the arms of said housing for supporting the heating elements.

9. In a device of the character described, the combination of heating elements and means for supporting the same, of a receptacle member comprising a housing, means for supporting said housing, and a plurality of receptacles in said housing connected in parallel so as to receive any one of the attachment plugs and complete the electrical 95 connection to the heating elements.

10. In a device of the character described, the combination of heating elements and means for supporting the same, of a receptacle member comprising a housing having 100 openings in its top for receptacles, a receptacle in each opening, a collar around each opening, said collar having depending ears, and a yoke connected to said ears for underlying and supporting the receptacle. 105

11. In a device of the character described, the combination of heating elements and means for supporting the same, of a receptacle member comprising a housing having openings in its top for receptacles, a receptacle in each opening, each receptacle having a single contact member, and a plurality of attachment plugs adapted to cooperate one with each receptacle. 110

12. In a device of the character described, the combination of heating elements and means for supporting the same, of a receptacle member comprising a housing having a series of openings arranged in rows side by side, receptacles arranged in each of said 120 openings, and means electrically connecting diagonally opposite receptacles so as to retain longitudinally and transversely adjacent receptacles of opposite polarity. 115

13. In a device of the character described, the combination of heating elements and means for supporting the same, of a receptacle member comprising a body of insulatory material, said body having a plurality of recesses and grooves registering with lon- 125 130

2

itudinal series of said recesses, bus bars in said grooves, and contact members carried by said bus bars and projecting into said recesses.

- 5 14. In a device of the character described, the combination of heating elements and means for supporting the same, of a receptacle member comprising a body of insulatory material, said body having a plurality

of recesses and grooves registering with longitudinal series of said recesses, bus bars in said grooves, contact members carried by said bus bars and projecting into said recesses, and polarized attachment plugs for cooperating with said contact member. 10

15 In testimony whereof I affix my signature.

SIDNEY S. BAND.
